UNITED STATES PATENT OFFICE

2,449,629

CHILD'S FOLDING SEAT

Edward B. Thompson, Downers Grove, Ill.

Application April 5, 1946, Serial No. 659,982

2 Claims. (Cl. 4—239)

1

My invention relates to a folding seat, and more particularly to a child's folding toilet seat.

One feature of my invention is that it provides an improved child's folding toilet seat; another feature of my invention is that it provides a child's toilet seat comprising a peripheral frame and a seat member which fold into a lightweight, compact unit which can be easily carried from place to place, and which can be carried in a small bag or case; a further feature of my invention is that it requires no fastening means such as hooks or latches to retain it in unfolded position; still a further feature of my invention is that its construction is such that it cannot collapse when in use; yet another feature of my invention is that it includes a seat member of flexible sheet material which can be readily removed from the frame for cleaning; and still another feature of my invention is that it provides depending elements to hold it in position on a conventional toilet seat.

My invention comprises a child's folding toilet seat which includes several advantages over any such seats heretofore known. First, it is desirable that such a seat be light in weight and be capable of being folded into a compact unit which may be easily carried from place to place and may be placed in a small case or bag if desired for use when the child is taken away from its home. Second, such a seat should be easy to fold or unfold, without the requirement of using hooks or latches. Also, such a seat should be of such a construction that it cannot collapse when in use, and it should have means to lock or hold it on the conventional toilet seat so that the child will not be injured while using the folding seat. Finally, it is desirable that such a folding seat be easily cleaned.

I have devised and am here disclosing a child's folding toilet seat which includes all these desirable features. It is light in weight, comprising only a peripheral frame which defines the external dimensions of the seat in a horizontal plane when the seat is normally positioned, and a seat member of flexible sheet material, as canvas for example. It is very compact, for the frame folds upon itself and the seat member wraps around the folded frame making a unit of small dimensions. Further, it is so constructed that it cannot collapse when a child is sitting upon it, and the construction includes depending elements to hold the folding seat in position upon a conventional toilet seat. Also, my improved folding seat includes provisions for readily removing the seat member so it may be more readily cleaned. Other features and advantages of my invention

2

will be apparent from the following specification and the drawings, in which:

Figure 1 is a plan view of my improved child's toilet seat in an unfolded position; Figure 2 is a front elevation of the seat shown in Figure 1, showing the means for removably fastening the seat member to the front frame member; Figure 3 is a sectional view of the seat taken on the line 3—3 of Figure 1; Figure 4 is a bottom plan view of the seat with the peripheral frame folded, but the seat member unfolded; and Figure 5 is a side elevation of the seat shown in Figure 4, with both the frame and the seat member folded.

Referring now to the drawings a folding frame 15 which defines the periphery or edges of the folding seat includes a rigid front member 10, a rigid back member 11 and a pair of folding side members 12a—12b and 13a—13b. Each side member is made of two separate pieces, as 12a and 12b, 20 which are joined in the center by the hinges 14 and 15, respectively. Such hinges are mounted on the outer side of each side member so that each side member can fold inwardly but cannot fold outwardly. Each side member is pivotally 25 connected at its ends to one end of the front and back frame members, respectively, by the hinges 16 and screws 17. The frame above described may be constructed of wood, metal, or other material, and when unfolded forms an approximate 30 square of a size of the same order as a conventional toilet seat.

Removably attached to the front and back frame members by means of the conventional snaps 18, is a seat member 19 which is constructed 35 of flexible sheet material, as for example canvas, and has an opening 20 therethrough as shown in Figure 1. In the particular embodiment of my invention shown in the drawings the seat member 19 is attached to the front frame member by 40 means of four snaps and is attached to the back frame member by means of three snaps, one on each end and one in the center. I have found such an arrangement to be desirable and advantageous, but other fastening means may be employed.

Mounted on the underside of the front frame member is a depending element 21, and mounted on the underside of the back frame member is a depending element 22. Elements 21 and 22 may 50 be formed of wood, metal or other material and perform the function of keeping the folding seat in its proper position on a conventional toilet seat.

In Figure 1 my improved folding seat is shown 55 in an unfolded position preparatory to use. It

will be readily seen that when a child is placed upon the seat the side members are prevented from collapsing inwardly by the body of the child, and are prevented from collapsing outwardly by the construction of the device, for with the hinges 14 and 15 placed on the outside edge of said side members the center ends of each section of each side member meet in such manner that the member cannot fold outwardly.

If it is desired to carry the folding seat from one place to another it may be folded without operating any hooks or latches, but merely by pushing the center of each side member of the frame inward and by such means the frame will collapse upon itself as shown in Figure 4. The seat member 19 may be then wrapped around the frame as shown in Figure 5, making a very compact unit which may be placed in a small bag or case. When the folding seat is again ready for use it may be set up in a very few seconds by merely unwrapping the seat member 19 and pulling the front and back frame members away from each other. If it is desired to clean the seat member 19 it may be readily removed from the frame by means of the conventional snaps 18.

While I have shown and described only one embodiment of my invention, it is to be understood that it is capable of many modifications. Changes, therefore, in the construction and arrangement may be made without departing from the spirit and scope of the invention as disclosed in the appended claims.

I claim:

1. A child's collapsible seat of the character described, including: a non-separable collapsible peripheral frame of a size of the same order as a conventional toilet seat, and comprising rigid

front and back members and a pair of side members permanently pivotally connected to the front and back members, each side member being hinged in the center in such manner as to be collapsible inwardly only; and a seat member of flexible sheet material having an opening therethrough and adapted to be fastened to the front and back members of the frame.

2. A child's collapsible seat of the character described, including: a non-separable collapsible peripheral frame of a size of the same order as a conventional toilet seat, and comprising rigid front and back members and a pair of side members permanently pivotally connected to the front and back members at the respective ends thereof, each side member being hinged in the center in such manner as to be collapsible inwardly only; and a seat member of flexible sheet material having an opening therethrough, said seat member being fastened only to said front and back members and the weight of a child's body on said seat member preventing said side members from collapsing inwardly.

EDWARD B. THOMPSON.
